CONTAINER

Original Filed Feb. 5, 1926

Inventor
Charles L'Enfant

By his Attorney *C. P. Gepel*

UNITED STATES PATENT OFFICE

CHARLES L'ENFANT, OF NEW YORK, N. Y.

CONTAINER

Application filed February 5, 1926, Serial No. 86,130. Renewed July 2, 1928.

This invention relates to containers, and has for its primary object to provide a case or container for cigarettes, cigars and other commodities which may be simply and inexpensively constructed, and will be convenient and serviceable in practical use.

It is a more particular object of the invention to provide a container having an article holder enclosed within two similar case sections hingedly connected at one of their ends for relative movement and to provide means constituting a connection between the article holder and the case sections and which also acts to yieldingly urge the case sections to closed positions. Also, in one embodiment of the invention, I may provide an additional flexible connection between the case sections and the article holder to positively limit the opening movement of the case sections.

With the above and other objects in view, the invention consists in the improved container and in the form, construction and relative arrangement of its several parts as may be hereinafter more fully described, illustrated in the accompanying drawings, and subsequently incorporated in the subjoined claims.

In the drawings, wherein I have illustrated one simple and practical embodiment of the invention, and in which similar reference characters designate corresponding parts throughout the several views,

Figure 1 is a perspective view showing the improved case or container closed;

Fig. 2 is a similar view, the case being open, and

Fig. 3 is an enlarged longitudinal section of the case with the parts in open position.

Referring in detail to the drawings, I provide an article holder 5 which may be of any desired capacity. As shown, this holder is adapted to receive a package of cigarettes and at one of its ends is entirely open so that the individual cigarettes can be readily withdrawn. At this open end of the holder, the side walls thereof are cut away as indicated at 6 to afford more convenient access to the contents of the holder.

The article holder 5 is enclosed within two

similar case sections 7. These case sections as well as the holder 5 may be conveniently stamped or formed from sheet metal. The sections 7 are preferably provided with the rounded or convex ends 8. Adjacent the lower end wall 8 of each case section and disposed in spaced parallel relation thereto a metal plate 9 is positioned between and suitably fixed to the side walls of the case sections. These side walls of the case sections are positioned in a common plane so that when closed the edges of said walls at the open sides of the case sections are in contact with each other. The corresponding ends of the metal plates 9 are connected by a suitable hinge 10 and said edges of the side walls of the case sections between this hinge and the bottom walls 8 of said sections are cut away or obliquely inclined in relatively opposite directions as indicated at 11.

The bottom wall 12 of the article holder 5 has centrally fixed therein a U-shaped clip 13 of spring metal, the arms of which extend through spaced slots in said walls 12 and through slots or openings in the plates 9 at opposite sides of the hinge 10, the free ends 14 of said clip being outwardly turned and engaged against the spaced edges 11 of the bottom walls 8 of the case sections as clearly shown in Fig. 3 of the drawings. The spaced arms of this clip 13 normally tend to assume a position in parallel relation to each other and urge the case sections 7 to the closed position shown in Fig. 1 of the drawings. If desired, the case sections 8 at their other or upper ends may be provided with any convenient latch means shown at 15 to retain said sections in closed positions.

While not an essential element of my present improvements, I may also provide a flexible strap 16 extending over the bottom wall 12 of the holder 5 and through openings at the ends thereof and suitably attach or connect the extremities of said strap as at 17 to the lower corners of the respective case sections 7. Thus, the length of the portions of this flexible strap extending between the attached end 17 at the corners of the case sections and the lower corners of the holder 5 will determine the permissible extent of rel-

ative opening movement of the case sections, thus avoiding excessive bending strain upon the spring clip 13.

From the above description, considered in connection with the accompanying drawings, the construction and manner of operation of the device will be readily understood. When it is desired to obtain access to the contents of the holder 5, the lower end portions of the two case sections 7 are grasped and swung in relatively opposite directions, such movement of the case sections being yieldingly resisted by the arms of the clip 13. Owing to the location of the hinge 10 and the provision of the inclined edges 11 on the lower ends of the case sections, this relative pivotal movement of the two sections is permitted notwithstanding the fact that the end walls of the case sections are of rounded or convex form. Thus, the cigarettes or other contents of the holder 5 will be exposed at the open end of the holder between the spaced ends of the case sections 7 so that the cigarettes may be readily withdrawn by the persons to whom they may be presented. Also, the user may readily open the case by moving one section thereof relative to the other with one hand while the other hand is used to withdraw the cigarettes. Immediately upon the release of the case sections, the spring clip 13 will return the same to closed position. It will thus be seen that this clip subserves the double purpose of retaining the article holder in proper position between the case sections and also for yieldingly urging said case sections to closed positions over the open end of said holder. Therefore, owing to the very simple form and construction of the several parts of the device, it will be apparent that the same can be manufactured and sold at comparatively small cost.

While I have herein shown one desirable embodiment of my present improvements, it will nevertheless be understood that the essential features thereof might also be incorporated in various other alternative structures, and I accordingly reserve the privilege of adopting all such legitimate changes therein as may be fairly embodied within the spirit and scope of the invention as claimed.

I claim:

1. A container comprising an article holder, an enclosing case therefor comprising two sections, a transverse hinge connecting said sections in spaced relation to the bottom end walls thereof, and means extending through the article holder and embracing the hinge, said means also engaging the bottom end walls of the case sections to urge the said case sections into closed position about the article holder.

2. A container comprising an article holder, an enclosing case therefor comprising two sections, a transverse hinge connecting said sections in spaced relation to the bot-

tom walls thereof, a resilient member extending through the bottom wall of the article holder and straddling the hinge and arms on the resilient member engaging the outer sides of the bottom walls of the enclosing sections for yieldably urging said sections into closed position about the article holder.

3. A container of the character described comprising an article holder, an enclosing case therefor consisting of two sections having corresponding side and end walls positioned in the same plane for edge to edge contact when the case is closed, the end walls of said case sections being rounded or convex, a transverse hinge connection between said case sections in spaced relation to the bottom end walls thereof, a member extending through the bottom wall of the article holder embracing the hinge connection and engaged with said bottom end walls of the case sections whereby said article holder is connected with said case sections, and means limiting the relative opening movement of the case sections.

4. A container of the character described comprising an article holder, an enclosing case therefor consisting of two sections having rounded or convex end walls, plates fixed between the side walls of each case section in spaced relation to the bottom end wall thereof and hingedly connected with each other at the edges of said side walls, said edges of the side walls of the case sections being obliquely inclined in opposite directions from said plates to the bottom walls of the case sections to permit of the relative pivotal movement of the case sections, and means engaged with the bottom wall of the article holder and yieldingly coacting with the bottom wall of the case section to retain said holder and the case sections in assembled relation.

5. A container of the character described comprising an article holder, an enclosing case therefor consisting of two sections having rounded or convex end walls, plates fixed between the side walls of each case section in spaced relation to the bottom end wall thereof and hingedly connected with each other at the edges of said side walls, said edges of the side walls of the case sections being obliquely inclined in opposite directions from said plates to the bottom walls of the case sections to permit of the relative pivotal movement of the case sections, a resilient metal clip engaged through the bottom wall of the article holder having spaced arms embracing said hinge and engaged with respective bottom walls of the case sections to yieldingly urge said case sections to closed position and retain the article holder in assembled relation with said case sections.

6. A container of the character described comprising an article holder, an enclosing case therefor consisting of two sections having rounded or convex end walls, plates fixed be-

- between the side walls of each case section in spaced relation to the bottom end wall thereof and hingedly connected with each other at the edges of said side walls, said edges of the side walls of the case sections being obliquely inclined in opposite directions from said plates to the bottom walls of the case sections to permit of the relative pivotal movement of the case sections, a resilient metal clip engaged through the bottom wall of the article holder having spaced arms embracing said hinge and engaged with respective bottom walls of the case sections to yieldingly urge said case sections to closed position and retain the article holder in assembled relation with said case sections, and additional means for positively limiting the relative opening movement of the case sections with respect to the article holder.
7. A container comprising an article holder, an enclosing case therefor consisting of two sections having a hinge connection between said case sections in spaced relation to the bottom walls thereof, and a member extending through the bottom wall of the article holder embracing the hinge connection and engaged with said bottom walls of the case sections whereby said article holder is connected with said case sections.
8. A container comprising an article holder, an enclosing case therefor, consisting of two sections adapted to close about said holder, a transverse hinge uniting said sections at a point adjoining the bottom of said holder, a resilient clip fixed in the bottom of the holder and having a pair of arms passing astride said hinge and through said sections and respectively tensioned directly upon said sections whereby to cause said sections to assume a closed position about said holder.

In testimony that I claim the foregoing as my invention, I have signed my name hereto.

CHARLES L'ENFANT.
